[57] CLAIM

The ornamental design for a credenza, as shown and described.

DESCRIPTION

FIG. 1 is a top perspective view of the credenza showing my new design;

FIG. 2 is an enlarged detail view of the left front, top corner shown in FIG. 1;

FIG. 3 is a front elevational view thereof;

FIG. 4 is a typical enlarged detail view of a pull handle shown in FIG. 1;

FIG. 5 is a right side elevational view, the left side view being a mirror image thereof;

FIG. 6 is a top plan view thereof;

FIG. 7 is a rear elevational view thereof;

FIG. 8 is a top perspective view of a second embodiment of my credenza;

FIG. 9 is a top perspective view of a third embodiment of my credenza.

FIG. 10 is a bottom perspective view of the second embodiment of my credenza illustrated in FIG. 8; and FIG. 11 is a bottom perspective view of the third embodiment of my credenza shown in FIG. 9.
